UNITED STATES PATENT OFFICE.

EDWIN O. LITTLE, OF ALEDO, ILLINOIS.

DESIGN FOR A CASING FOR ADVERTISING DEVICE.

Application filed February 23, 1928. Serial No. 25,541. Term of patent 14 years.

To all whom it may concern:

Be it known that I, EDWIN O. LITTLE, a citizen of the United States, residing at Aledo, in the county of Mercer and State of Illinois, have invented a new, original, and ornamental Design for Casing for Advertising Device, of which the following is a specification, reference being made to the drawings, forming a part thereof.

In the annexed drawings Fig. 1 is a perspective view of a casing for an advertising device constructed in accordance with my invention; Fig. 2 is an end view thereof; Fig. 3 is a front elevation and Fig. 4 an end view from the opposite end to that shown in Fig. 2.

I claim:

The ornamental design for a casing for advertising device as shown.

EDWIN O. LITTLE.
